CASING FOR A THERMOSTAT, OR THE LIKE

Frank B. Roth, Richmond Heights, Mo., assignor, by
mesne assignments, to White-Rodgers Company, a cor-
poration of Delaware

Application September 21, 1956, Serial No. 43,037

Term of patent 14 years

(Cl. D52—7)

FIG. 4

FIG. 2

FIG. 1

FIG. 3

Fig. 1 is a front view of a casing for a thermostat with the hinged cover closed, showing my new design;

Fig. 2 is a top plan view of the casing shown in Fig. 1;

Fig. 3 is a front view of the casing with its hinged cover opened 90°;

Fig. 4 is a top plan view of the casing with its hinged cover opened 90°.

I claim:

The ornamental design for a casing for a thermostat, or the like, substantially as shown.
